UNITED STATES PATENT OFFICE

PAISLEY B. HARWOOD, OF MILWAUKEE, WISCONSIN, ASSIGNOR, BY MESNE ASSIGNMENTS, TO CUTLER-HAMMER, INC., OF MILWAUKEE, WISCONSIN, A CORPORATION OF DELAWARE

CONTROLLER FOR ELECTRICALLY-OPERATED SKIP HOISTS

Application filed October 4, 1926. Serial No. 139,425.

63. This invention relates to controllers for electrically-operated skip hoists.
- The invention relates more particularly to controllers for double bucket skip hoists although certain features thereof may be advantageously employed in controllers for skip hoists of the single bucket type.
- The invention has among its objects to provide an improved controller for double bucket skip hoists wherein provision is made for insuring raising of the loaded bucket and lowering of the empty bucket upon successive operations of a single starting switch.
- Another object is to provide a controller of the aforesaid character including control means for stopping the skip hoist at any point and for insuring restarting thereof in the proper direction to raise the loaded bucket upon operation of the aforementioned starting switch.
- Another object is to provide a controller of the aforesaid character wherein provision is made for lowering a loaded bucket from any point at a reduced rate of speed by operation of a "down" push button.
- Another object is to provide a controller of the aforesaid character having emergency control means associated therewith which provides for operation of the skip hoist in either direction at either a low or a high speed.
- Various other objects and advantages of the invention will hereinafter appear.
- The accompanying drawings illustrate an embodiment of the invention which will now be described, it being understood that the embodiment illustrated may be modified in certain respects without departing from the spirit and scope of the appended claims.
- In the drawing,
49. Figure 1 is a schematic and diagrammatic view of a controller embodying the invention, the circuit connections being omitted.
- Fig. 2 is an across-the-line diagram of the motor connections together with the control circuit for a brake associated with the motor, and
53. Fig. 3 is an across-the-line diagram of the control circuits for the several control elements illustrated in Fig. 1.
55. Referring to Fig. 1 the same illustrates a motor M for driving a drum D of a skip hoist. The operating cable or cables extend in the usual manner around drum D and are connected to the skip buckets so that during operation of the motor in one direction one of the skip buckets is raised and the other is lowered, while reversal of the motor reverses the direction of operation of the skip buckets. The motor M may be of any desired type, but in the embodiment illustrated the same is shown as of the compound type. Also, in the embodiment illustrated the motor M is provided with an electromagnetically operated brake B.
- As shown in Figs. 1 and 2 the armature circuit for motor M is controlled by a knife switch 1, an electromagnetically operated main switch 2, and two sets of electromagnetically operated reversing switches 3-4 and 5-6 and the current in said circuit is controlled by means of series resistances R¹ to R⁵, inclusive, and shunt resistances R⁶ to R¹⁰, inclusive. Resistances R¹ to R⁵, inclusive, have electromagnetically operated control switches 7 to 11 associated therewith, the switches 7 to 10 being arranged to connect resistances R² to R⁵ respectively in shunt with the resistance R¹ and the switch 11 being arranged to shunt resistances R¹ to R⁵, inclusive. Resistances R⁶ to R¹⁰, inclusive, are controlled by electromagnetically operated switches 12 to 16, respectively, the switches 12 to 15 being normally closed and the switch 16 being normally open. The shunt field F¹ of the motor is controlled by a double pole double throw knife switch 17, said knife switch being adapted in one position to connect said field to lines L¹ to L², and being adapted in its other position to connect a discharge resistance across the terminals of said field. The brake B associated with the motor is controlled by a normally open electromagnetic switch 18.
- The control means for the set of reversing switches 3-4 includes a normally open double pole electromagnetically operated relay 20 while the control means for the other set of reversing switches 5-6 includes a normally open double pole electromagnetically operated relay 21. Each of the relays 20 and 21

21 is also arranged to control main switch 2, accelerating switch 15 and the brake switch 18. The control means further includes relays 22 and 23 to be energized simultaneously with relays 20 and 21 respectively. Each of the relays 22 and 23 is provided with two sets of normally open contacts and a set of normally closed contacts, and as hereinafter set forth said relays serve to control certain of the accelerating switches. Relays 20 to 23, inclusive, are all controlled through the medium of safety switches including an overspeed governor switch 25, overload switches 26 and 27 and a pair of slack cable switches 28 and 29, all of said switches being arranged in series in the energizing circuits of the aforementioned relays. In addition to the aforementioned switches relays 20 to 23, inclusive, are controlled through the medium of a "Stop" snap switch 30, and a normally open "Hoist" push button switch 31, said switches being adapted as hereinafter set forth to control the aforementioned relays through the medium of the aforescribed safety devices and a selector relay 35.

Relay 35 is of the double pole double throw type, the same being provided with an operating winding 35^a and a latching coil 35^b. The arrangement is such that upon energization of the operating winding 35^a the selector switch is moved to one extreme position and is held therein by a latching mechanism and upon deenergization of winding 35^a and energization of coil 35^b the latching mechanism is released to permit the selector switch to return to normal position. As hereinafter set forth the operating winding 35^a of the selector switch 35 is controlled through the medium of a limit switch 36 while the trip coil 35^b is controlled through the medium of a limit switch 37. The arrangement is such that when one of the buckets of the skip hoist is brought into one extreme position the operating winding 35^a is energized to move the selector relay 35 into its latched in position while when said bucket is moved into its opposite extreme position the trip coil 35^b is energized to permit the selector relay 35 to return to normal position. As hereinafter set forth the selector relay 35 selects the direction of operation of the motor so that upon successive operations of the "Hoist" push button 31 raising of the loaded skip bucket is always insured. The limit switches 36 and 37 also serve as hereinafter set forth to insure interruption of the energizing circuits of relays 20 to 23, for stopping of the motor when the skip buckets are moved into their limits.

Accelerating switches 7 to 11, inclusive, are controlled through the medium of an electromagnetically operated timing device 40 and relays 41 to 45, inclusive, having operating windings arranged in series with re-

sistances R¹ to R⁵ respectively. Relays 41 to 45, inclusive, are each adapted under given conditions in the motor circuit to establish energizing circuits for accelerating switches 7 to 11 respectively while the timing device 40 is adapted to establish energizing circuits for said accelerating switches independently of said relays if the latter do not close within a given interval. Timing device 40 is of a well known type, the same being provided with a series of contact fingers which are adapted to close successively against the action of a dash pot upon energization of an operating winding 40.

The control means for slow down switches 12, 13 and 14 includes limit switches 50 to 55, inclusive. As hereinafter set forth limit switches 50, 51 and 52 are adapted to be operated in the order named prior to limit switch 37 during movement of the skip hoist into one of its limits, while limit switches 53, 54 and 55 are adapted to be operated in the order named prior to limit switch 36 during movement of the skip hoist into an opposite limit.

As before stated the switch 18 for controlling brake B is controlled by relays 20 and 21, and as hereinafter set forth said switch is also controlled by a relay 56 arranged in series in the armature circuit of the motor.

With the control means above described, depression of the hoist push button 31 causes the motor to be brought up to speed automatically to operate the skip hoist in a direction to raise the loaded bucket, and when the skip hoist moves into either of its limits the same is automatically stopped. Furthermore as hereinafter set forth the skip hoist can be stopped at any intermediate point by opening the stop switch 30 and can then be restarted by the push button 31 in a direction to raise the loaded bucket.

In some instances it is desirable to provide means whereby the operator can lower a loaded bucket and for this purpose relays 60 and 61 are provided which effect substantially the same control as relays 20 and 21 respectively. Relays 60 and 61 are both controlled by electro-responsive relays 62 and 63 which also control the accelerating switch 16. Relays 62 and 63 are controlled by a lowering push button 64 through the medium of certain of the contacts of the selector switch 35 and said lowering push button also acts through the medium of said selector switch to control relays 65 and 66 which are adapted as hereinafter set forth to control the slow down switches 12, 13 and 14.

It is desirable to provide in addition to the operator's control means an emergency control for operating the skip hoist in either direction at a high or a low speed. For this purpose control of the aforescribed relays and switches is transferred to an emergency master drum 70 by means of a 12 pole double

throw knife switch 71. For control of the skip hoist from the push button station the transfer switch 71 is maintained in its lower position as shown in Fig. 1, and when it is desired to control from the emergency drum the same is moved into its upper position. The master drum includes stationary contacts 72 to 81, inclusive, movable contact 72^a and 73^a to cooperate with contact 72 and 73 and two sets of movable contacts arranged on opposite sides of said stationary contacts. One of said sets of movable contacts includes contacts 74^a to 79^a, while the other set of movable contacts includes contacts 74^b, 75^b, 76^b, 79^b, 80^b and 81^b. One of the poles of the knife switch 71 serves to establish an energizing circuit for a no voltage relay 90, and said relay serves as hereinafter set forth to necessitate return of the master drum 70 to off position as a prerequisite to starting of the motor.

In addition to the aforescribed control means a knife switch 91 is provided for controlling the line connections of all of the aforescribed relays and such line connections are further controlled by a normally open relay 92 having its operating winding permanently connected in series with the shunt field F¹.

The operation of the aforescribed controller together with the circuit connections therefor will now be more fully described in connection with Figs. 2 and 3. Assuming that all of the control elements are in the position shown in Fig. 1 and upon closure of the stop snap switch 30 and depression of the hoist push button 31, relays 20 and 22 are energized by a circuit extending from line L¹ through the over speed governor 25 and overload devices 26 and 27 through one pole of the transfer switch 71, through the stop button 30 and another pole of the transfer switch 71, through normally closed auxiliary contacts 11^b associated with accelerating switch 11 through the hoist push button 31, through the upper left hand pole of the selector relay 35 to and through the operating windings of the relays 20 and 22 in parallel, through down contacts of relays 23 and 65 through the lower pole of the limit switch 37 and thence through the normally closed auxiliary contacts 7^b of accelerating switch 7 and the slack cable switches 28 and 29 to line L², it being assumed that the relay 92 is closed due to current in the shunt field circuit. Upon closure of relay 22 the left hand pole thereof shunts hoist switch 31 to establish a maintaining circuit for said relay 22 and also relay 20. Also upon closure of relay 22 the right hand pole thereof energizes slow down switches 12, 13 and 14 through the medium of limit switches 50, 51 and 52 and the auxiliary contacts associated with reversing switch 3 while the lower pole of said relay prevents energization of relays 21 and 23. Upon closure of re-

lay 20 the set of reversing switches 3-4 is energized by a circuit extending from line L¹ through the lower pole of limit switch 37, through one pole of the transfer switch 71 through the left hand pole of relay 20 and another pole of the transfer switch 71 to and through the operating windings of reversing switches 3 and 4 in parallel and through the lower pole of limit switch 37, contacts 7^b and slack cable switches 28 and 29 to line L². Also, immediately upon response of reversing switch 4 the main switch 2 and accelerating switch 15 are energized by a circuit extending from line L¹ to the relay 20 as already traced, through the right hand pole of said relay, through one pole of the transfer switch 70 to and through the operating windings of main switch 2 and accelerating switch 15 in parallel, through auxiliary contacts 4^b associated with reversing switch 4 and thence through the lower pole of limit switch 37 to line L² as already traced. Switch 4 in responding also bypasses contacts 7^b by means of its auxiliary contacts 4^c. Upon closure of main switch 2 and reversing switches 3-4 the motor starts to operate at a reduced speed with the series resistances R¹ to R⁵ in circuit therewith and the shunt resistances R⁶ to R¹⁰ excluded from circuit. Immediately upon starting of the motor, the series brake relay 56 closes and the operating winding of the brake switch 18 is then connected in parallel with the operating windings of main switch 2 and accelerating switch 15. Brake switch 18 in responding maintains itself through the medium of auxiliary contacts 18^b and connects the brake operating winding between lines L¹-L² through the main switch 2.

Upon the closure of accelerating switch 12 the timing device 40 is energized by a circuit extending from line L¹ through the normally closed down contacts of relays 62 and 63 through one pole of the transfer switch 71, through auxiliary contacts 11^c of accelerating switch 11 through auxiliary contacts 18^c associated with the brake switch 18 to and through the operating winding 40^a of said timing device through auxiliary contacts 12^b of accelerating switch 12 through the lower pole of the limit switch 50 and thence through the auxiliary contacts of reversing switch 3 to line L².

Immediately upon establishment of the motor circuit the relay 41 is energized and when the current in the motor circuit drops to a given value said relay closes to establish an energizing circuit for the accelerating switch 7 extending from line L¹ through the normally closed contacts of relays 63 and 62 through one pole of the transfer switch 71 through said series relay and the operating winding of the accelerating switch 7 and thence through the auxiliary contacts 2^b associated with main switch 2 to line L¹. If the series relay 41 does not return to normal

position prior to movement of the first contact finger of the timing device 40 into closed position the operating winding of switch 7 will be connected directly to line L^1 by said contact finger. Upon closure of accelerating switch 7 resistance R^2 is connected in parallel with resistance R^1 and relay 42 responds. Under given current conditions in the motor circuit relay 42 returns to normal position to energize the operating winding of accelerating switch 8, such energizing circuit extending from line L^1 through the normally closed contacts of relays 62 and 63 through one pole of the transfer switch 71, through the auxiliary contacts 11^c of accelerating switch 11, through series relay 42 and the operating winding of accelerating switch 8, through the auxiliary contacts 7^c of accelerating switch 7 and thence through the auxiliary contacts 12^b of accelerating switch 12, through the lower pole of limit switch 50 and the auxiliary contacts associated with the reversing switch 3 to line L^1 . If the series relay 42 does not return to normal position prior to movement of the second contact finger of the timing device into closed position accelerating switch 8 is energized independently of said relay by connection thereof directly to line L^1 . Accelerating switch 8 in responding connects resistance R^3 in parallel with resistances R^1 and R^2 and series relay 43 then responds. Under given current conditions in the motor circuit relay 43 returns to normal position to establish an energizing circuit for the accelerating switch 9 extending from line L^1 through the series relay 43, the auxiliary contacts 8^b associated with accelerating switch 8 and through the operating winding of said accelerating switch to line L^2 . If the relay 43 does not return to normal position within a given interval the third contact of timing device 40 closes to connect the operating winding of accelerating switch 9 to line L^2 independently of the series relay 43. Accelerating switch 9 in closing connects resistance R^4 in shunt with resistances R^1 , R^2 and R^3 and the series relay 44 responds. Under given current conditions in the motor circuit relay 44 returns to normal position to connect the operating winding of accelerating switch 10 across lines L^1 — L^2 through the medium of the auxiliary contacts 9^b associated with accelerating switch 9. If relay 44 does not return to normal position within a given interval the fourth contact finger of the timing device 40 closes to connect the operating winding of accelerating switch 10 to line L^1 . Accelerating switch 10 in closing connects resistance R^5 in shunt with resistances R^1 , R^2 , R^3 and R^4 for further acceleration of the motor. Series relay 45 then responds to current in the motor circuit and under given current conditions the same returns to normal position to energize accelerating switch

11 through the medium of the auxiliary contacts 10^c associated with accelerating switch 10. If series relay 45 does not close within a given interval the last contact finger of the timing device 40 connects the operating winding of accelerating switch 11 directly to line L^2 . Switch 11 in closing shunts all of the resistances R^1 to R^5 for full speed operation of the motor. Also, upon closure of accelerating switch 11 the same interrupts the aforescribed energizing circuit for timing device 40 by opening of the auxiliary contacts 11^c and said accelerating switch maintains itself in closed position by a circuit extending from line L^1 through the normally closed contacts of relays 63 and 62 through a pole of the transfer switch 71 through auxiliary contacts 11^d associated with said accelerating switch through the operating winding of said accelerating switch through auxiliary contacts 12^b of accelerating switch 12 through the lower pole of limit switch 50 and thence through the auxiliary contacts associated with reversing switch 3 to line L^1 . The skip hoist will now operate to bring the loaded bucket into its upper position and during movement of the bucket into such position limit switches 50, 51, 52 and 37 are operated in the order named. Upon opening of limit switch 50 the upper pole thereof interrupts the aforescribed energizing circuit for accelerating switch 12 and switch 12 in closing includes resistance R^6 in the motor circuit to reduce the motor speed. Also upon opening of limit switch 50 the lower pole thereof interrupts the aforescribed energizing circuit for accelerating switches 8 and 11 and switch 8 in opening causes accelerating switches 9 and 10 to open. Resistances R^1 , R^4 and R^5 are thus excluded from the motor circuit while accelerating switch 7 is maintained in closed position by the auxiliary contacts of main switch 2 to connect resistance R^2 in shunt with R^1 . Opening of limit switches 51 and 52 effects deenergization of accelerating switches 13 and 14 in the order named to include resistances R^7 and R^8 in the motor circuit. The skip hoist then opens the final limit switch 37 which interrupts the aforescribed energizing circuits for main switch 2, reversing switches 3—4, accelerating switch 15, brake switch 18 and the relays 20 and 22. Main switch 2 in opening deenergizes accelerating switch 7 for exclusion of resistance R^2 and the motor is then brought to rest under the action of its brake B.

The controller is now set so that if the hoist button 31 is again operated the motor will be reversed to elevate the bucket which was formerly empty but which, it is assumed, is now loaded. Such setting of the controller is obtained by means of the selector relay 35. Upon the aforescribed movement of the skip hoist into its limit, the upper pole of the limit switch 37 establishes

- an energizing circuit for the trip coil 35^b of the selector relay 35, such energizing circuit extending from line L¹ through the aforementioned pole of limit switch 37 through said trip coil and then through auxiliary contacts 35^c associated with the selector switch 35 to line L². Upon tripping of the latching mechanism of the selector switch 35, the upper contact fingers thereof are opened while the lower contact fingers close. With the selector switch 35 in this position upon depression of the hoist push button, relays 21 and 23 are energized by a circuit extending from line L¹ to the hoist push button as hereinbefore traced through the lower left hand pole of the selector switch 35 to and through the operating windings of relays 21 and 23 in parallel, through the normally closed contacts of relays 64 and 22 through the lower pole of limit switch 36 through the auxiliary contacts 7^b of accelerating switch 7 to and through the slack cable switches 28 and 29 to line L². In responding relay 21 establishes an energizing circuit for reversing switches 5 and 6 extending from line L¹ through the upper pole of limit switch 36 through one pole of the transfer switch 71 through the right hand pole of relay 21 through another pole of the transfer switch 71 to and through the operating windings of reversing switches 5 and 6 and then through the lower pole of limit switch 36 to line L² as already traced. Also, upon closure of relay 21 the same functions in substantially the same manner as relay 20 to establish the aforescribed energizing circuits for main switch 2, accelerating switch 15 and the brake switch 18 through the medium of the lower pole of limit switch 36, one of the poles of transfer switch 71 and auxiliary contacts 7^b associated with accelerating switch 7 and upon closure of reversing switch 5 the contacts 7^b are by-passed by auxiliary contacts 5^c. Also, relay 23 in responding functions in substantially the same manner as relay 22 to shunt the hoist push button, establish an energizing circuit for the slow down switches 12, 13 and 14 and to render the relays associated with the up reversing switches inoperative. The control mechanism operates in substantially the same manner as above described to operate the skip hoist in a reverse direction. As the skip hoist moves into its opposite limit limit switches 53, 54, 55 and 36 are operated in the order named to perform substantially the same functions as the limit switches 50, 51, 52 and 37 respectively, as above described. However, in this connection it should be noted that the upper pole of limit switch 36 resets selector switch 35 through the medium of auxiliary contacts 35^a.
- The skip hoist can be stopped at any point between limits by opening of the stop push button switch 30 and upon stopping of the skip hoist at any point the selector switch
- 35 always insures operation of the motor in a direction to raise the loaded bucket upon starting of the motor by the hoist push button 31. Assuming now that the skip hoist has been stopped in an intermediate position while the same was operating in a direction corresponding to reversing switches 3-4. Upon depression of the lowering push button 64 relays 63 and 65 are energized by a circuit extending from line L¹ through the overspeed governor 25, overload devices 26 and 27, one pole of the transfer switch 71, stop button 30, another pole of the transfer switch 71, the auxiliary contacts 12^b associated with accelerating switch 12 through the lowering push button 64 through the upper left hand contacts of selector switch 35 through the operating windings of the relays 63 and 66 in parallel, through the normally closed contacts of relays 65 and 22, through the lower pole of limit switch 36, through auxiliary contacts 7^b associated with accelerating switch 7 and the slack cable switches 28 and 29 to line L².
- Relay 63 in responding establishes an energizing circuit for slow speed switch 16 extending from line L¹ through the left hand pole of said relay, through one pole of the transfer switch 71 and thence through the operating winding of accelerating switch 16 to line L². Upon closure of accelerating switch 16 the relay 61 is energized by connection thereof in parallel with the operating winding of accelerating switch 16 through the medium of the left hand pole of relay 66. Relay 61 is connected in shunt with the relay 21 and performs substantially the same functions as the latter. In other words, upon closure of relay 61 the main switch 2 and reversing switches 5 and 6, accelerating switch 15, brake switch 18 are all closed to reverse the direction of operation of the motor for lowering of the loaded bucket.
- Relay 63 in responding maintains itself and relay 66 through the medium of its right hand contacts while the normally closed contacts thereof render the timing relay 40 and accelerating switch 7 inoperative to prevent operation of the accelerating switches 7 to 11, inclusive. Also, relay 66 in responding establishes energizing circuits for slow down switches 12, 13 and 14 through the medium of limit switches 53, 54 and 55, respectively and the auxiliary contacts associated with reversing switch 6. Thus it should be noted that during lowering operations of the loaded bucket the series resistance R¹ and shunt resistance R¹⁰ are included in the motor circuit to provide for slow operation of the motor. During lowering of the loaded bucket into its lower limits switches 53, 54 and 55 are opened in the order named to deenergize slow down switches 12, 13 and 14 respectively for inclusion of resistance R⁶, 130

R⁷ and R⁸, while upon movement of the loaded bucket into its lower limits the limit switch 36 is opened to again stop the motor as hereinbefore described. In this connection it should be noted that the selector switch 35 remains in its original position.

Assuming now that the skip hoist was operating in a direction corresponding to the reversing switches 5 and 6 and that the same was stopped at an intermediate point it will be observed that the selector switch 35 is in a position whereby its lower contacts are closed whereby depression of the lowering push button will effect energization of relays 62 and 65 by a circuit extending from line L¹ to the lowering button as hereinbefore described through the left hand down contact of relay 35 through operating windings of relays 62 and 65 in parallel through the normally closed contacts of relays 23 and 65 through the lower pole of limit switch 37 through auxiliary contacts 7^b of accelerating switch 7 and through the slack cable switches 28 and 29 to line L². Relay 62 performs substantially the same functions as relay 63 during the hereinbefore described lowering operation of the loaded skip hoist and relay 65 provides for energization of relay 60 by a circuit extending from line L¹ through the left hand pole of relay 62 through one pole of the transfer switch 71, through the auxiliary contacts of accelerating switch 16 and through the left hand pole of relay 65 to and through the operating winding of relay 60 to line L². Relay 60 in responding performs substantially the same function as relay 20 whereby the motor is caused to operate in a direction which is opposite to that of which it was assumed it was to be last operating.

As before stated the controller includes an emergency control drum 70 which is adapted to act through the transfer switch 71 to selectively effect high and low speed operation of the skip hoist in opposite directions. Assuming that the transfer switch 71 is moved into its upper emergency position the no voltage relay 90 is energized by a circuit extending from line L¹ through one pole of the transfer switch 71 to stationary contact 73 through movable contacts 73^a and 72^a to stationary contact 72 through another pole of the transfer switch, through the overspeed governor 25, overload devices 26 and 27, another pole of the transfer switch 71 and thence through the operating winding of the no voltage relay to line L². Upon response of voltage relay 90 the left hand pole thereof bypasses contacts 72, 72^a, 73 and 73^a. Upon movement of the emergency drum 70 towards the left into either its slow or fast speed positions, reversing switches 3 and 4 are energized by a circuit extending from line L¹ through the upper pole of limit switch 37 through a pole of the transfer switch 71 to

stationary contact 77 of the master controller and thence through contacts 77^a, 78^a and 78 through another pole of the transfer switch 71 to and through the operating windings of reversing switches 3 and 4 to line L² as hereinbefore traced. Also circuit is established from line L¹ to contact 78^a as already traced through contacts 79^a, 79 to and through the right hand pole of the no voltage relay 90 through one pole of transfer switch 71 and thence to the operating windings of main switch 2 accelerating switch 15 and the brake switch 18. When the master switch is moved towards the right into either its slow or high speed positions the same is adapted to energize the set of reversing switches 5 and 6 by a circuit extending from line L¹ through the upper pole of limit switch 36, through transfer switch 71 to contact 81 and thence through contacts 81^b, 80^b and 80, through one pole of transfer switch 71 to and through the operating windings of reversing switches 5 and 6 to line L² as already traced. Also circuit is established from line L¹ to contact 81 as already traced through contacts 81^b, 79^b and 79 to and through the right hand pole of no voltage relay 90, through one pole of the transfer switch 71 to the operating windings of main switch 2, accelerating switch 15 and the brake switch 18.

It is thus apparent that the emergency drum 70 provides for operation of the motor in either direction selectively and in this connection it should be noted that under no voltage conditions no voltage relay 90 prevents re-starting of the motor except upon return of said drum to off position. In other words, the no voltage relay prevents energization of either set of reversing switches or main switch 2, accelerating switch 15 and the brake switch 18 except upon return of the drum 70 to off position, which serves as hereinbefore described to establish an energizing circuit for the no voltage relay.

Also when the emergency drum 70 is moved into either of its slow speed positions circuit is established from line L¹ through the left hand pole of the no voltage relay 90 to contact 72, through contacts 75^a or 75^b to contact 75 through one pole of the transfer switch 71 to and through the operating winding of switch 16 to line L². As before stated response of switch 16 insures slow speed operation of the motor and it should be noted that when the drum 70 is moved into either of its fast speed positions such switch is de-energized. The drum 70 is also adapted in both of its slow and fast speed positions to connect the slow down switches 12, 13 and 14 to line L¹ through the medium of contacts 72, 72^a, 74^a or 74^b, whereby said switches will act in the manner hereinbefore described to effect slow down of the motor during movement of the skip hoist into either of its limits. Upon movement of the drum 70 into either of

its fast speed positions the accelerating switches 7 to 11, inclusive, are rendered operative by by-passing the normally closed contacts of relays 62 and 63 through the medium of contacts 72, 72^a, 76^a or 76^b and 76.

What I claim as new and desire to secure by Letters Patent is:

1. In combination, two skip buckets, a motor for moving said skip buckets oppositely between upper and lower limits, control means for said motor including a selector switch to be set in different positions upon movement of said skip buckets into corresponding limits, a hoist push button and a lowering push button for controlling said motor through the medium of said selector switch and means associated with said former means for insuring operation of said motor at a given speed during hoisting of a loaded bucket, and at a lesser speed during lowering of a loaded bucket. 70
2. In a skip hoist the combination with two skip buckets, of a motor for operating said buckets oppositely between upper and lower limits, starting means for said motor including a selector switch to be set in one position upon movement of one of said skip buckets into a given limit and in another position upon movement of the other of said skip buckets into a corresponding limit, means including a manually operated push button adapted to act through the medium of said selector switch to insure operation of the motor in a direction to raise a loaded skip bucket, and a second manually operated switch arranged to act through said selector switch to effect operation of said motor in a direction for lowering of a loaded skip hoist bucket. 75
3. The combination with an electric motor, of switches for establishing reverse power connections therefor, and control means for said reversing switches including a selector switch to be set in different positions upon operation of said motor in opposite directions through a given range and a single control switch adapted upon successive operations to control said reversing switches through the medium of said selector switch for operation of said motor in opposite directions through said range. 80
4. The combination with an electric motor, of switches for selectively establishing reverse power connections therefor and control means for said reversing switches including an electroresponsive switch having a plurality of operating windings associated therewith for effecting setting thereof in different positions upon operation of said motor in opposite directions through a given range and a manually operated control switch adapted upon successive operations to control said reversing switches through the medium of said selector switch for operation 85
- of said motor in opposite directions through said range. 90
5. The combination with an electric motor, of switches for selectively establishing reverse power connections therefor and control means for said reversing switches including a selector switch adapted to be set in different positions upon operation of said motor in opposite directions through a given range and a plurality of manually operated switches for controlling said reversing switches through the medium of said selector switch, one of said manually operated switches being adapted upon successive operations to effect operation of said motor in opposite directions through said range, another being adapted to stop said motor at intermediate points in said range and another being adapted upon stopping of said motor at any intermediate point to restart the same in an opposite direction. 95
6. The combination with an electric motor, of switches for selectively establishing reverse power connections therefor, a manually operated control switch, means for selectively controlling said reversing switches upon successive operations of said control switch to effect operation of said motor in opposite directions through a given range and push button controlled means associated with said former means for stopping said motor at intermediate points in said range and for restarting the same in an opposite direction. 100
7. The combination with an electric motor, of electroresponsive switches for selectively establishing reverse power connections therefor, a manually operated control switch, means for selectively controlling said reversing switches upon successive operations of said control switch to effect operation of said motor in opposite directions between given limits at a given speed and means for stopping said motor at points between said limits and for restarting the same in an opposite direction at a reduced speed. 105
8. In combination, a skip bucket, an operating motor therefor, means including a single push button adapted upon successive operations to control said motor for operation of said bucket in opposite directions at a given speed between the loading and dumping positions thereof, and means associated with said former means including a push button for controlling said motor to effect lowering of said bucket from any intermediate point at a reduced speed when the same is loaded. 110
9. In combination, a skip bucket, an operating motor therefor, means including a single push button adapted upon successive operations to control said motor for operation of said bucket in opposite directions at a given speed between the loading and dumping positions thereof and means associated 115

- 130

with said former means including a plurality of push buttons, one for controlling said motor to stop said bucket at any intermediate point and the other for controlling said motor to effect lowering of said bucket from any intermediate point at a reduced speed when the same is loaded.

In witness whereof, I have hereunto subscribed my name.

PAISLEY B. HARWOOD.
